SPRINKLER

John A. Royer, Fresno, Calif., assignor to Buckner
Manufacturing Company, Fresno, Calif., a co-
partnership

Application February 17, 1950, Serial No. 144,649

8 Claims. (Cl. 299—69)

1

This invention is directed to, and it is an object to provide, an improved irrigation sprinkler of the type which includes a rotary head moved step by step through the medium of actuating mechanism recurrently impinged by a water stream issuing from a nozzle mounted on said head; the sprinkler being especially designed, but not limited, for use in connection with a portable, agricultural sprinkling system.

Another object of the invention is to provide a rotary sprinkler, of the step by step motion type, which will function properly at relatively low water pressure; this being a condition which frequently exists in portable irrigation systems wherein a multiplicity of sprinklers are simultaneously fed from a common feed pipe.

A further object of the invention is to provide a sprinkler, as aforesaid, wherein the actuating mechanism includes, with a vertically swingable arm, a novel water deflection spoon on an outer end of the arm adapted to be recurrently impinged by the stream of water from a nozzle; each impingement of the spoon with the stream causing the sprinkler to part-rotate one step and the spoon and arm to swing down to clear the stream preparatory to a return up-swing for the next step in the operation.

An additional object of the invention is to provide a sprinkler, as in the preceding paragraph, wherein said spoon has a novel functional configuration which assures of the desired lateral shifting motion of the spoon, and resultant step by step rotation of the sprinkler, under conditions of relatively low water pressure as aforesaid; i. e. a relatively low pressure water stream directed against the spoon from the corresponding nozzle.

It is also an object of the invention to provide a sprinkler which is designed for ease and economy of manufacture; the sprinkler being of simplified construction, well balanced, and functioning smoothly when in operation.

Still another object of the invention is to provide a practical and reliable sprinkler, and yet one which will be exceedingly effective for the purpose for which it is designed.

These objects are accomplished by means of such structure and relative arrangement of parts as will fully appear by a perusal of the following specification and claims.

In the drawings:

Fig. 1 is a side elevation of the sprinkler.

Fig. 2 is a top plan of the sprinkler.

Fig. 3 is a fragmentary longitudinal section of the spoon, on line 3—3 of Fig. 2.

Referring now more particularly to the char-

2

acters of reference on the drawings, the sprinkler comprises an upstanding, Y-shaped rotary head, indicated generally at 1; such head being of tubular construction and including opposed branches 2 and 3, together with a depending attachment neck 4 which is coupled by a swivel joint 5 to a fitting 6. The fitting 6 is adapted to be secured by threading onto the upper end of a water pressure supply riser 7, as in a portable irrigation system or the like.

The branches 2 and 3 are each fitted, at their outer ends, with a nozzle; such nozzles being indicated at 8 and 9, respectively. As the nozzles extend axially from the branches 2 and 3, the streams of water emit from said nozzles with an upward and outward divergence.

A swing arm 10 is disposed laterally of one side of the Y-shaped rotary head 1 and is mounted for vertical swinging or oscillating motion in the following manner:

Intermediate its ends the swing arm 10 is fixed to a horizontal cross shaft 11 which extends inwardly through the crotch of the Y-shaped rotary head 1, being turnably supported in a transverse boss 12 separate from said head. The transverse boss 12 is in integral connection, by means of a neck 13, with an upstanding axis boss 14 disposed in the direction of the nozzle 9 and turnably engaged on an upstanding stud 15 fixed to the branch 3 intermediate its ends; such stud being at substantially a right angle to the axis of said branch 3.

The upstanding axis boss 14 is turnably maintained on the stud 15 by means of a hold-down washer 16 and a cotter pin 17 which extends through said stud.

The transverse boss 12 is formed, on the side opposite the neck 13, with an integral extension 18 which projects longitudinally of, and in overhanging relation to, the branch 2; such extension 18 having a longitudinally outwardly opening, generally U-shaped notch 19 therein, and a nub 20 upstanding from the branch 2 engages in said notch. The notch 19 is of greater width than the nub 20, whereby the transverse boss 12 is capable of slight rocking motion with the stud 15 as an axis; the boss 14 correspondingly part-turning about said stud. The purpose of the above rockable mount for the transverse boss 12 will hereinafter appear.

The swing arm 10 projects some distance beyond the nozzle 9, and at the corresponding end is formed with a water deflection spoon, indicated generally at 21; such spoon extending laterally inwardly from the swing arm and in starting

position being directly in line with the stream of water from the nozzle 9.

The inner or working face of the spoon, as indicated at 22, curves inwardly from top to bottom and is formed, diagonal to the longitudinal axis of the stream of water from the nozzle 9, with the diagonal in a direction such that when said stream of water strikes the spoon the latter is urged in a clockwise direction, as indicated by the arrow in Fig. 2. In other words, the leading edge of the working face 22 of the spoon 21 is closer to the axis of rotation of the head 1 than the trailing edge of said spoon.

The clockwise motion of the spoon 21 under the influence of the stream of water from the nozzle 9 is enhanced by forming inwardly extending lips 23 and 24 on the top and leading edges, respectively, of said spoon. Thus, when a water stream from the nozzle 9 strikes the spoon 21, considerable pressure is built up on the working face 22 in the direction of the lip 24; the latter retarding such pressure and the resultant counter-effect assuring of a clockwise motion of the spoon 21.

The swing arm 10 is fitted, on the rear end portion thereof; i. e. opposite the spoon 21, with an adjustable counterweight 25 held in position by a set screw 26, the counterweight 25 tending to swing the arm 10 in a direction to raise the spoon 21 to its uppermost position, which uppermost position is controlled by a stop screw 27 threaded through a laterally projecting finger 28 on the boss 14. The finger 28 overhangs the swing arm 10 ahead of the cross shaft 11, and the stop screw 27 is abutted by said arm from below.

When the above described sprinkler is in operation, water from the nozzle 9, impinging upon the water deflection spoon 21, causes said spoon to shift clockwise a short distance, and at the same time to swing downward, clearing the spoon from the stream. As the spoon 21 shifts clockwise such short distance a rocking motion is first imparted to the transverse boss 12, and a sharp impact occurs between the notched extension 13 and the nub 20, setting up a vibration in the head 1 whereby said head, under continued clockwise motion of the spoon 21, freely takes a step or part-turn movement.

After each down swing of the arm 10, the counterweight 25 swings the spoon end of the arm upward, whereupon the next step in the operation takes place. Such upswing can be supplemented, if desired, by a torque spring (not shown) working between the cross shaft 11 and transverse boss 12.

The speed of swinging motion of the arm 10 is regulated by adjustment of the counterweight 25, which adjustment thus also controls the speed of the step-by-step motion of the rotary head 1.

In order to permit the spoon 21 on each upstroke to return to its uppermost limit of movement; i. e. its proper starting position, a laterally inwardly projecting baffle 29 is formed on the swing arm 10 intermediate the spoon 21 and nozzle 9. The action of this baffle 29 is to break up or disturb the stream of water from the nozzle 9, as the arm 10 swings upward, at the proper moment to permit the spoon 21 to return to its starting position in the normal path of said stream.

By reason of the particular configuration of the spoon; the positioning of the cross shaft 11 directly above the vertical axis of the sprinkler, with resultant excellent balance; and the jarring or impacting feature attained by use of the

notched extension 13 and hub 20, the sprinkler works smoothly and effectively, even under conditions of relatively low water pressure. The sprinkler is thus admirably suited for use in connection with portable, agricultural irrigation systems which many times work under high pressure.

Another advantage of the described design is that the swing arm 10, together with the associated fitting, including the bosses 12 and 14, can be readily detached from the remainder of the sprinkler merely by removing the cotter pin 17 and sliding the boss 14 off the stud 15. This expedites repair or replacement of parts, and additionally facilitates initial manufacture of the device.

From the foregoing description it will be readily seen that there has been produced such a device as substantially fulfills the objects of the invention, as set forth herein.

While this specification sets forth in detail the present and preferred construction of the device, still in practice such deviations therefrom may be resorted to as do not form a departure from the spirit of the invention as defined by the appended claims.

Having thus described the invention, the following is claimed as new and useful, and upon which Letters Patent are desired:

1. A water deflector for the vertically swingable weighted arm of a step-by-step lateral-nozzle rotary sprinkler in which said arm extends ahead of the nozzle; the deflector comprising a spoon having a transversely flat and relatively wide working face curving upwardly and forwardly from below and normally extending thence across the path of the stream issuing from the nozzle and lying diagonal thereto, and a lip extending along the upper edge of said working face normally above the axis of the stream and projecting in the direction of the nozzle.

2. A deflector as in claim 1, in which the lip is of substantially semi-circular form in cross section.

3. In the combination of a rotary vertical-axis sprinkler head having a nozzle projecting laterally from its upper end and a rearwardly weighted swing arm disposed to one side of the head and having a deflector element ahead of the nozzle for recurring engagement by the stream from the nozzle; means mounting the arm for vertical swinging movement including a pivot pin extending transversely of the nozzle, and means supporting the pin from the head so that the axis of the pin substantially intersects the axial line of the head.

4. In the combination of a rotary vertical-axis sprinkler head having a nozzle projecting laterally from its upper end and a rearwardly weighted swing arm disposed to one side of the head and having a deflector element ahead of the nozzle for recurring engagement by the stream from the nozzle; means mounting the arm for vertical swinging movement including a pivot pin extending transversely of the nozzle and directly over the head, and means supporting the pin from the head, and adjustment means acting on the arm to limit the upward swing of the arm and enable the normal position of the deflector relative to the stream to be selectively altered.

5. In the combination of a rotary vertical-axis sprinkler head having a nozzle projecting laterally from its upper end and a rearwardly weighted swing arm disposed to one side of the head and having a deflector element ahead of the nozzle

for recurring engagement by the stream from the nozzle; means mounting the arm for vertical swinging movement including a pivot pin extending transversely of the nozzle and directly over the head, and means supporting the pin from the head to allow of limited lateral swinging movement of the arm.

6. A structure as in claim 5 in which said last named means comprises a transverse boss in which the pin is mounted, a stud upstanding from the head ahead of the boss, an upstanding boss rigid with the transverse boss and turnable on the stud, and means limiting rotation of the upstanding boss on the stud.

7. A structure as in claim 6 in which said limiting means comprises an extension on and projecting rearwardly from the transverse boss and overlying the head, the extension having an opening therein extending lengthwise of the arm and a nub fixed on the head and projecting into the head in loose-play relation to the sides thereof.

8. A structure as in claim 6, with a vertically

adjustable element on the upstanding boss overhanging the arm ahead of the pivot pin to limit upward swinging of the arm and enable the deflector element to be set in a selected position relative to the stream from the nozzle.
